CLAIM

The ornamental design for a retail packaging for consumable products, as shown and described.

DESCRIPTION

FIG. 1 is a perspective view of an embodiment of the retail packaging;

FIG. 2 is a front view of the retail packaging of FIG. 1; FIG. 3 is a rear view of the retail packaging of FIG. 1; FIG. 4 is a side view of the retail packaging of FIG. 1; FIG. 5 is a side view of the retail packaging of FIG. 1; FIG. 6 is a top view of the retail packaging of FIG. 1 in an opened configuration;

FIG. 7 is a bottom view of the retail packaging of FIG. 1; FIG. 8 is a top perspective view of the retail packaging of FIG. 1 with the top in an opened configuration; and, FIG. 9 is a perspective view of the retail packaging of FIG. 1 having the consumable products residing within the receiving compartment of the retail packaging.

The broken line showing of portions of the retail packaging for consumable products is included for the purpose of illustrating environmental structure and forms no part of the claimed design.
